UNITED STATES PATENT OFFICE.

WILLIAM SHORE, OF MINNEAPOLIS, MINNESOTA.

STOKER.

1,203,063.

Specification of Letters Patent. Patented Oct. 31, 1916.

Application filed March 24, 1916. Serial No. 86,494.

To all whom it may concern:

Be it known that I, WILLIAM SHORE, a citizen of the United States, residing at Minneapolis, in the county Hennepin and State of Minnesota, have invented certain new and useful Improvements in Stokers; and I do hereby declare the following to be a full, clear, and exact description of the invention, such as will enable others skilled in the art to which it appertains to make and use the same.

My invention relates to automatic stokers and has for its object to provide a simple and efficient agitator for preventing clogging of coal in a hopper.

To the above ends, generally stated, the invention consists of the novel devices and combinations of devices hereinafter described and defined in the claim.

20 In the accompanying drawings which illustrate the invention, like characters indicate like parts throughout the several views.

Referring to the drawings: Figure 1 is a side elevation with some parts broken away and some parts sectioned, showing my invention applied to a stoker of commercial form; Fig. 2 is a fragmentary detail in section approximately on the line $x^2 x^2$ of Fig. 1, 30 some parts being shown in full; Fig. 3 is a section taken approximately on the line $x^3 x^3$ of Fig. 2, some parts being removed and some parts being indicated by dotted lines; Fig. 4 is a view in section on the line $x^4 x^4$ of Fig. 3; and Fig. 5 is a plan view of the parts shown in Fig. 1, some portions being broken away and some being removed.

In stokers of standard construction, it is a common practice to force the granulated or fine coal from a hopper to the grates by a multiplicity of alternately reciprocated plungers. The coal, much of which is in the form of dust, has a tendency to get clogged in the hopper, or in the discharge spout 45 from the bottom of the hopper to the plunger seat, and it does this by a sort of a bridging action which holds back the coal and prevents the proper supply to the feed plungers.

50 I provide an extremely simple and efficient agitator within the hopper and operate this agitator in an extremely simple and efficient way from the alternately reciprocated feed plungers.

55 In the drawings, the hopper 1 is connected by a depending spout portion 2 to an oblique

feed spout 3 that is formed integral with the plunger cylinders or seats 4. The delivery spout 3 directs the coal to the grates, not shown.

Working within the plunger 4 are feed plungers 5 connected by links 6 to the cranks 7 of a crank shaft 8 that is journaled in suitable bearings 9 shown as secured to the heads of the respective cylinders. This crank shaft 8 is rotated by power mechanism of well known arrangement. The two feed plungers 5, at the extreme outsides, are given their reciprocating movements in alternate order, and each is provided with a grate shaking connection including thrust rods 10 mounted to slide through guide lugs 1^a on the sides of the feed spout 6 and having their outer ends 10^a connected to studs 11 carried by the said outside feed plungers 73 and working through longitudinal slots 12 in the outside cylinders 4. The mechanism so far specifically described, is that of a standard stoker now found in commercial use.

The agitator comprises a rotary shaft 13 journaled in bearings formed on the end plates of the hopper 1 and provided within the hopper with radially projecting pins 14. On each projecting end of the shaft 13 is a ratchet wheel 15 connected to and rotated therewith, and, as shown, keyed thereto by a key 16 extended diametrically through the shaft with its ends engaging notches formed in the coöperating ratchet wheel. Each 85 ratchet wheel coöperates with a gravity-held driving dog 17 carried by a ratchet lever 18. Each ratchet wheel 18 is provided with laterally spaced head plates 19 that are pivoted on the end of the shaft 13 and embrace the 90 coöperating ratchet wheel and key 16, thereby holding the said ratchet wheel engaged with the coöperating key. The said head plates 19 are suitably bolted or riveted to the respective levers 18. The depending free 95 ends of the said levers 18 stand in position to be engaged by the heads 10^a of the grate agitating rods 10. The driving dogs 17 of the two levers 18 and the coöperating ratchet wheels are arranged to drive the shaft 13 in 100 a constant direction, and, as the two outside feed plungers 3 and, consequently, the agitating rods 10, are given their inward and outward movements in alternate order, it is evident that one of the said levers will 105 impart rotary motion to the said agitating shaft while the other is making a returning

stroke, and that this relation will be alternated so that an approximately continuous rotation of the agitating shaft in a constant direction, will be produced. The rotation of 5 the agitating shaft will keep the pulverized or dust coal in motion, thereby preventing clogging and serving to break down any bridge formation which may tend to form the coal while on its way to the feed 10 plungers. Any coal that is once thrown in front of the feed plungers will, of course, be positively forced onward to the grates of the furnace.

As illustrated, the pawl-equipped levers 18 15 are gravity-retracted and their pawls 17 are gravity-held in operative engagement with the teeth of the coöperating ratchet wheels.

It will be noted that I have, by utilizing the alternate movements of the outside feed

plungers, provided an extremely efficient 20 agitator at very small cost.

What I claim is:

In a stoker, the combination with a hopper and alternately reciprocated feed plungers working at the bottom thereof, of a rotary agitator working in said hopper, a pair of ratchet wheels secured to said agitator, and pawl-equipped levers coöperating with 25 said ratchet wheels and arranged to be vibrated in alternate order by the said alternately reciprocated feed plungers.

In testimony whereof I affix my signature in presence of two witnesses.

WILLIAM SHORE.
